UNITED STATES PATENT OFFICE

97,425

DESIGN FOR A VENDING MACHINE CASING

Harold Witte, North Kansas City, Mo., assignor to Peerless Products Company, North Kansas
City, Mo., a corporation of Missouri

Application March 20, 1935, Serial No. 55,963

Term of patent 3½ years

To all whom it may concern:

Be it known that I, Harold Witte, a citizen of the United States, residing at North Kansas City, in the county of Clay and State of Missouri, have invented a new, original, and ornamental Design for a Vending Machine Casing, of which the following is a specification, reference being had to the accompanying drawing, forming part thereof.

In the drawing:

I claim:

The ornamental design for a vending machine casing, substantially as shown.

Signed at North Kansas City, in the county of Clay and State of Missouri, this 14th day of March, 1935.

HAROLD WITTE.
